UNITED STATES PATENT OFFICE.

ARTHUR ERNEST JERRAM, JOSEPH GOULDBOURN, AND FRED RICKS, OF LEICESTER, ENGLAND, ASSIGNEES TO UNITED SHOE MACHINERY CORPORATION, OF PATERSON, NEW JERSEY, A CORPORATION OF NEW JERSEY.

PULLING-OVER MACHINE.

1,426,390.

Specification of Letters Patent. Patented Aug. 22, 1922.

Original application filed September 28, 1916, Serial No. 122,631. Divided and this application filed March 15, 1920, Serial No. 366,030. Renewed February 16, 1922. Serial No. 537,134.

To all whom it may concern:

Be it known that we, ARTHUR E. JERRAM, JOSEPH GOULDBOURN, and FRED RICKS, subjects of the King of England, residing at 5 Leicester, in the county of Leicestershire, England, have invented certain Improvements in Pulling-Over Machines, of which the following description, in connection with the accompanying drawings, is a specification, like reference characters on the drawings indicating like parts in the several figures.

This invention relates to machines for pulling uppers over lasts and more particularly to machines including in their organization upper pulling means and fastening mechanism for securing the margin of the upper on the bottom of the last, this application being a division of our prior application Serial No. 122,631, filed on September 28, 1916 wherein are claimed per se certain features of the fastener feeding and driving means hereinafter described.

Features of the present invention reside 25 in a novel organization of upper pulling and fastening means and means for effecting transfer or feed of a fastener or fasteners at a predetermined time in the cycle of the machine, the machine herein shown 30 being so constructed as to pull the upper over a last positioned bottom downward and having mechanism which is operative at a predetermined time relatively to the operation of the upper pulling means to deliver 35 fasteners point upward to the fastener driving means. In one of its important novel aspects the invention provides pneumatic means for feeding fasteners at a predetermined time in relation to the upper pulling 40 operation, and as herein shown under control of the upper pulling means, the pneumatic means in the illustrative machine being so constructed as to invert the fasteners and present them point upward relatively to a shoe positioned bottom downward for the pulling-over operation.

The above and other features of the invention, including certain details of construction and combinations of parts, will 50 now be described with reference to the accompanying drawings and pointed out in the claims.

In the drawings:

Fig. 1 is a view in side elevation of a machine in which the invention is embodied;

Fig. 2 is a detail view in elevation of a portion of the pneumatic means for effecting transfer of the fasteners, with portions of the mechanism shown in section;

Fig. 3 is a section on the line 3—3 of Fig. 2;

Fig. 4 is a view in elevation, and partly in section, of a portion of the mechanism shown in Fig. 2 as viewed from the right hand side of said figure with the parts in a different position from that indicated in Fig. 1;

Figs. 5 and 6 show respectively a portion of the tack separating mechanism as constructed in the present machine and as commonly used heretofore;

Fig. 7 is a view in vertical section through a portion of the tack transferring mechanism;

Fig. 8 is a detail plan view of a portion of the mechanism shown in Fig. 7;

Fig. 9 shows in elevation the upper end of one of the driver bar arms and its associated tack carrier.

Fig. 10 is a plan view of the mechanism seen in Fig. 9, different positions of a portion of the mechanism being indicated respectively by full and by dotted lines; and

Fig. 11 shows in elevation a portion of the mechanism shown in Fig. 9 as viewed from the left hand side of said figure.

The machine herein shown includes in its general organization many features of a well known type of pulling-over machine such as exemplified in prior United States Letters Patent No. 663,777, granted on December 11, 1900 upon an application of R. F. McFeely, and exemplified also in various modifications in other United States Letters Patent of which it is only necessary herein to refer to Patent No. 1,029,387, granted on June 11, 1912 upon an application of R. F. McFeely, to which patents reference may be made for an understanding of details not hereinabove fully described. In order to assist in understanding the present invention, certain general features of construction of the illustrative machine, some of which form the subject-matter of Letters Patent

No. 1,346,256 granted on July 13, 1920 upon an application of Fred Ricks and assigned to the assignee of this invention, will first be briefly described, and where convenient the reference characters of the prior Patent No. 663,777, and in certain instances also of Patent No. 1,029,387, will be used to indicate corresponding parts.

The operative parts of the machine are supported upon a frame comprising front and rear plates 2 and 4 respectively, connected by stay rods 6. Bolted to the front frame plate 2 and suitably supported at the top of the rear plate 4 is the head portion 8 of the machine upon which are mounted the various instrumentalities for operating upon the shoe, and operating means for such instrumentalities comprising the cam shaft D which in the present construction is supported vertically with its driving pulley 986 in a horizontal position between the frame plates. The operation of the machine is controlled by a treadle X⁵⁴ connected to one end of a lever X⁸³, to the other end of which is pivoted a short rod X⁵⁶ which serves in the manner described in said prior patents, upon the operation of the treadle, to actuate automatic means for retracting a brake shoe 982 from the pulley 986, such means acting through a rod X⁸⁴ and a lever X⁸⁵ to operate a rod 984 whereby the clutch (not shown) is actuated to cause the pulley 986 to be driven by means of a suitable belt to effect the first portion of the cycle of operations of the machine, after which the clutch is automatically disconnected and the brake applied through the connections above described by such means as are fully disclosed in prior Patent No. 663,777.

When the work is in position in the machine the last, with the upper position loosely upon it, is supported, as indicated by dotted lines in Fig. 1, with the rear portion of the upper on the last in engagement with a heel rest 10 and with the fore part of the sole or insole on the last positioned upon a sole rest 12. In this position the upper is engaged by the usual toe and side grippers, of which the toe gripper is seen at 14 in Fig. 1, and is pulled over the last automatically during the first portion of the cycle of operations, the machine then coming automatically to a stop. The toe gripper is connected to an "updraw" lever e which is pivoted on a rod 152 and has connection at its rear end through a rod 170 and a spring 176 with a cam slide 172 operated by a cam on the cam shaft D. Through movement of the slide 172 the toe gripper is thus operated to pull the upper yieldingly with a force determined by the degree of compression of the spring 176. The side grippers are similarly operated by levers 154 pivoted on the rod 152 and connected through springs 146 and rods 136 to a cam

slide 134. During a subsequent portion of the cycle, which takes place upon another depression of the treadle X⁵⁴, the margin of the upper is carried inwardly under the bottom of the last and, following movement of driver bar arms 672, 674 and 676 inwardly under the last bottom, the tacks are driven to retain the upper in its pulled-over position. While the machine is at rest after the first period of the cycle, the operator is afforded opportunity to effect such change of tension or such adjustment of the upper on the last as may be necessary in order to correct any inaccuracy in its position, through the manipulation of various instrumentalities of which it is only necessary herein to refer to handles 158 which comprise upwardly and forwardly curved extensions of the side gripper levers 154, and a handle e² comprising a similar extension of the toe gripper operating lever e, whereby the operator is enabled to manipulate the different grippers as desired. Pivoted on the handle e² is a lever 226¹ connected by a link 226¹¹ to the usual lever 226, whereby the opening of the toe gripper may be effected.

The work positioning means and the operating instrumentalities above described are so arranged in the machine shown that the heel end of the last is supported substantially over the front frame plate 2 of the machine and the last is inclined upwardly from its heel end toward the rear of the machine at such an angle that the operator, as he maintains a natural attitude at the front of the machine, may, without special effort, look downwardly and forwardly upon the top and sides of the forepart of the upper on the last and keep the work continuously in view in this manner until the operations are completed. The various instrumentalities whereby adjustment of the upper may be effected, comprising particularly the handles 158 and e², together with the lever 226¹, are, moreover, arranged in such relation to the work and to the position of the operator that he may manipulate them without the necessity of changing materially his viewpoint with reference to the work and without in any way obstructing his view of the work. In order to insure these results the handles referred to are preferably extended, as shown, to positions somewhat higher than the work and far enough forwardly to permit the operator to manipulate them without stooping. In the construction shown the last is positioned at an incline of substantially 50 degrees to the horizontal, this angle having been determined as particularly satisfactory for the objects in view under average working conditions, but it should be understood that the invention is not limited to a construction in which the last is inclined at the precise angle shown. It will be observed by reference to Fig. 1

that the operative portions of the machine are substantially at the rear of a vertical projection of the treadle X⁵⁴, and by reason of this arrangement the operator may maintain a single position close to the work both for operating the treadle and for manipulating the upper on the last.

The construction shown is particularly adapted for driving fasteners in the form of tacks, as is usual in machines of this type, but the invention in its broader aspects is not limited in respect to the form of the fastener. For assorting and arranging the tacks the machine shown includes a tack pot 400 of any usual form and raceways 16, equal in number to the number of tacks to be driven at each operation, upon which the tacks hang suspended in rows by their heads. The tack pot 400, in the construction shown, is supported upon a bracket 18 and is rotated from the cam shaft D through connections including a bell-crank 20 and a link 22. Mounted to reciprocate in the usual manner at the lower ends of the raceways 25 are separator plates 24 (Fig. 7) which are so formed (Fig. 5) that when the tack, shown at a, has been advanced to the inner end of the groove 26, it is still suspended by its head and is not permitted to drop 30 through the usual opening 562 in separator plate 558 (Fig. 6) as heretofore constructed. The tack, as thus supported, is moved into alignment with an opening 28 in the bracket plate 30 which serves to support the raceways. Communicating with this opening at its lower end is a pipe 32 which leads to a valve 34 arranged to control the admission to the pipe 32 of compressed air from a supply pipe 36 which may communicate with an 35 air pump or with any suitable supply of air under pressure. The construction shown comprises a single pipe 32 leading to the several openings 28, but it will be understood that several conduits 32 may be arranged to communicate with the several openings if desired. Positioned over the separators 24 is a bar 38 provided with openings 40 which are over the heads of the respective tacks after the latter have been 40 moved by the members 24 to separated position. Associated with each of the openings 40 is a block 42 pivoted to the bar 38 and having an opening 44 arranged to align with the opening 40 when the block 42 is 45 in the position shown in Fig. 7 and in full lines in Fig. 8. Raceway covers 46 rest upon the blocks 42, and upon the lifting of any one of these covers the corresponding block may be swung aside, as indicated by dotted lines in Fig. 8, in order to permit the raceway to be cleared in case a tack becomes wedged therein.

Supported at one end in the bar 38 and communicating with the respective openings 40 are curved conduits 48 which lead to

various points of delivery or presentation for the tacks to permit them to be supplied to the different tack driving instrumentalities. The conduits 48 are, it will be understood, equal in number to the number of 70 tacks to be driven at each operation and are grouped and arranged as required with reference to the particular points at which the tacks are to be driven in the work, the delivery ends of these conduits being supported on brackets 50 on the machine frame. With this construction and arrangement, a blast of compressed air from the pipe 32 will lift the tacks from the separator plates 24 and force them head foremost into and 80 through the respective conduits 48 to their points of delivery, the curved form of the conduits 48 causing the tacks in their passage to become inverted in such manner as to be finally presented point upward. 85

The driver bar arms 672, 674 and 676 have their usual movement toward and from driving positions with respect to the margin of the last bottom. With reference to Figs. 9 and 10, the driver bar arm 676, 90 which is one of the side arms having means for driving two tacks simultaneously in the side margin of the last bottom, is arranged for movement toward the left into position to drive the tacks and toward the right away 95 from the last to its inoperative position, the arm being shown in these figures as in position to permit the tacks to be driven. It will be noted that the delivery ends of the corresponding conduits 48 are positioned 100 adjacent to and at one side of the path of movement of the driver bar arm, and the machine is provided with means controlled by the movement of the arm for effecting a transfer of the tacks from delivery position 105 into position to be driven. The construction shown for effecting this transfer comprises a carrier plate 52 pivoted at 54 on the upper end of the driver bar arm, the plate having tack pockets 56 normally closed 110 at their lower ends by a spring pressed gate 58 provided with a sloping face 60 arranged to be engaged by the ends of the drivers 614 in their driving movement to cause the plate 58 to be pushed aside and permit the drivers 115 to enter the tack pockets and expel the tacks therefrom. The plate 52 is provided with a tail portion 62 having surfaces 64 and 66 arranged to engage a stud 68 on the bracket 50 to determine the position of the plate, the tail 62 being held in engagement with the stud by means of a spring 70 connected at one end to the tail and at its other end to a projection on the driver bar arm. When the parts are in the positions indicated in Figs. 120 9 and 10 the surface 64 is in engagement with the stud 68 and the plate 52 is positioned in such relation to the drivers 614 and the tack block that the tacks are supported 125 point upward in the pockets 56 and are in 130

position to be driven upon the operative movement of the drivers. When the driver bar arm is moved to its inoperative position, which is toward the right in Figs. 9 and 10, the stud 68, in co-operation with the surface 66, permits the plate 52 to be swung by the spring 70 about the axis 54 to the dotted line position (Fig. 10), in which the pockets 56 are in line with the delivery ends of the conduits 48. While the transfer plate is in this position tacks are forced through the conduits 48 and deposited, point upward, in the pockets 56 in the manner hereinbefore described. While the tack transferring means is illustrated in detail in its relation to only one of the driver bar arms, it will be understood that each of the arms has similar mechanism associated therewith.

In order to control the admission of compressed air to the conduit 32, the valve 34 is connected to a short shaft 72 upon which is secured a hub 74 provided with diametrically opposite ratchet teeth 76. Mounted loosely on the shaft 72 is an arm 78 provided with a spring pressed pawl 80, the arm 78 being rigid with a pinion 82 which is arranged to be turned in opposite directions alternately by the movement of a rack bar 84. The bar 84 is arranged to be moved toward the right (Fig. 1) during the pulling movement of the grippers in the first period of the cycle of operations of the machine through connection of the bar with one of the side lever updraw rods 136 by means of an angled arm 86 which is fast on the rod and bears at its outer end upon a collar 88 on the bar 84. During this movement, whereby the pawl 80 is turned about the hub 74 to cause it to engage the diametrically opposite teeth 76 without operating the valve 34, a spring 90 on the bar 84 is compressed and a dog 92 on the bar 84 is caused to engage a spring catch 94, whereby the rack bar is retained in the position to which it is moved. In the latter part of the final period of the cycle of operations of the machine the return of the arm 86 effected by the return movement of the gripper operating cam slide 134 causes a trip 96 on the arm to engage the catch 94 and withdraw it from the dog 92 against the pressure of its spring in such manner as to permit the spring 90 to force the rack bar toward the left and effect an opening and a closing movement of the valve 34, movement of the rack bar in this direction being retarded by means of a dash pot 98. In this manner a blast of air is forced through the pipe 32 and the tacks are delivered pneumatically point upward to the carrier plates at a time when these plates are positioned to receive them while the driver bar arms are in their retracted positions away from the shoe.

In the use of the machine the operator stands close to the front frame plate 2 in position to operate the treadle X⁵⁴. The work, positioned within easy reach of the operator, as indicated in dotted lines in Fig. 1, is below the level of the operator's eyes and is inclined at such an angle as to afford the operator full view of the top of the upper and the portions round the sides of the forepart of the last without any special effort upon his part such as would cause fatigue. The various handles which frequently require manipulation for the purpose of adjusting the upper, including the handles 158 and e², are so arranged as to be within easy reach of the operator as he stands in the position described without obstructing his view of the work. Upon the first depression of the treadle X⁵⁴ the upper is pulled over the last in the well known manner through the action of the grippers, and at the same time the rack bar 84 is retracted in preparation for the subsequent operation of the valve 34, the driver bar arms at this time being held in retracted position with the pockets 56 of the carrier plates 52 in line with the conduits 48 from which they have received inverted tacks in a previous operation of the machine. Upon a subsequent depression of the treadle, after any necessary adjustment of the upper on the last has been effected, the margin of the upper is carried inwardly under the last bottom, the driver bar arms move inwardly causing the plate 52 to swing about their pivots and carry the tacks into alignment with the drivers, and through the operation of the drivers the tacks are driven upwardly into the upper and the sole or innersole. The driver bar arms are then swung outwardly and cause the pockets 56 again to align with the conduits 48, and substantially simultaneously, as the grippers are returned to starting position, the valve 34 is operated in the manner described to cause the several tacks supported on the separator plates 24 to be lifted and forced through the conduits 48 and deposited point upward in the pockets 56 which arrive in alignment with the conduits in time to receive the tacks.

Although the invention has been described with reference to a particularly illustrative embodiment, it will be understood that various modifications in details are contemplated within the spirit and scope of the claims.

It should be understood that the term "inverted", except where the context requires a more limited interpretation, is used herein in a relative sense referring to substantial reversal of the position of a fastener end for end irrespective of any particular position which the fastener may occupy prior to such reversal.

Having described the invention, what we claim as new and desire to secure by Letters Patent of the United States is:

1. In a machine of the class described, the combination with means for pulling an upper over a last positioned bottom downward, of upwardly movable drivers for inserting fasteners on the bottom of the last to retain the upper in its pulled-over position, a source of supply for fasteners comprising means for suspending the fasteners point downward, and means for transferring the fasteners into position to be inserted by said drivers comprising pneumatic means dependent for its operation upon a movement of the upper pulling means for inverting the fasteners to present them with their points directed upward. 5
2. In a machine of the class described, the combination with means for pulling an upper over a last and means for driving fasteners to retain the upper in pulled-over position, of a source of supply for fasteners, means for utilizing compressed air to transfer fasteners from said source of supply toward the driving means with the fasteners determinately positioned during such transfer, a valve for controlling the compressed air supply, and means controlled by the upper pulling means for operating said valve. 10
3. In a machine of the class described, the combination with means for pulling an upper over a last and means for driving fasteners to retain the upper in pulled-over position, of a source of supply for fasteners, means for utilizing compressed air to transfer fasteners from said source of supply toward the driving means, a valve for controlling the compressed air supply, valve operating spring means, means connected with the upper pulling means for putting said valve operating means under stress upon a movement of the pulling means to pull the upper over the last, and means for tripping the valve operating means to cause the valve to open and close upon a reverse movement of the pulling means. 15
4. In a machine of the class described, the combination with upper pulling means, of fastener driving means movable into and out of driving position, means for supplying fasteners to the driving means comprising pneumatic means for effecting a transfer of the fasteners, and means controlled by the movement of the upper pulling means for rendering said pneumatic means operative when the driving means is out of driving position. 20
5. In a machine of the class described, the combination with upper pulling means and fastener driving means, of means for operating said upper pulling and fastener driving means to cause them to perform their respective operations with reference to the work in different respective periods of the cycle, means for supplying fasteners to the driving means comprising means for utilizing compressed air to effect a transfer of the fasteners, a valve for controlling the compressed air supply, valve operating spring means, means for putting said valve operating means under stress during the first period of the cycle of operations, and means for tripping said operating means to effect a transfer of fasteners during the final period of the cycle of operations. 25
6. In a pulling over machine, the combination with means comprising a reciprocatory member for pulling an upper over a last and means for driving fasteners to hold the upper in pulled-over position, of a source of supply for fasteners, and pneumatic means arranged to be actuated by movement of said reciprocatory member for transferring fasteners from said source of supply toward the driving means. 30
7. In a pulling-over machine, the combination with reciprocatory means for pulling an upper over a last and means for driving fasteners to hold the upper in pulled-over position, of a source of supply for fasteners, a conduit for conducting fasteners from said source of supply toward the driving means, means comprising a valve for directing compressed air into said conduit to force a fastener through the conduit, and means connected to said reciprocatory pulling-over means for actuating said valve by movement of said pulling-over means in one direction. 35
8. A machine of the class described having, in combination, power operated upper pulling means for stretching an upper over a last positioned bottom downward, mechanism for driving fasteners upwardly into the shoe to secure the upper in pulled-over position, a source of supply for fasteners constructed to support the fasteners point downward, and means automatically operative at a determinate time relatively to the operation of the upper pulling means to transfer fasteners from said source of supply and present them point upward to the fastener driving mechanism. 40
9. A machine of the class described having, in combination, grippers for engaging an upper at the toe end and at opposite sides of a last positioned bottom downward, power operated means for effecting relative movement of the last and the grippers to pull the upper, fastener inserting mechanisms at the toe end and at opposite sides of the last for driving fasteners upwardly into the shoe to secure the upper in pulled-over position, a source of supply for fasteners in which they are positioned point downward, transferring means for the fasteners comprising conduits leading from said source of supply to the different fastener in- 45
- 105
- 110
- 115
- 120
- 125
- 130

serting mechanisms and constructed to invert the fasteners and deliver them point upward to said mechanisms, and means dependent for its operation upon a relative 5 movement of the grippers and the last for forcing fasteners through said conduits.

10. A machine of the class described having, in combination, power means automatically operative to pull an upper over a last positioned bottom downward and to come to a stop with the upper held under tension, mechanism for driving fasteners upwardly into the shoe to secure the upper in pulled-over position upon a subsequent starting 15 of the machine, and means automatically operative in the course of the cycle of operations of the machine to deliver fasteners point upward to said fastener driving mechanism for use in the operation of the machine on the next shoe.

11. A machine of the class described having, in combination, power means automatically operative to pull an upper over a last positioned bottom downward and to come to a stop with the upper held under tension, mechanism for driving fasteners upwardly to secure the upper in pulled-over position upon a subsequent starting of the machine, a source of supply for fasteners in which 25 they are positioned point downward, and means automatically operative in the course of the cycle of operations of the machine to transfer fasteners from said source of supply and deliver them point upward to the 30 fastener driving mechanism.

12. A machine of the class described having, in combination, power means automatically operative to pull an upper over a last and to come to a stop with the upper held under tension, fastener inserting mechanism for fastening the upper in pulled-over position upon a subsequent starting of the machine, and pneumatic means automatically operative in the final period of the cycle of 45 operations of the machine to deliver fasteners to said fastener inserting mechanism for use in the operation of the machine on the next shoe.

13. In a machine of the class described, the combination with means for pulling an upper over a last positioned bottom downward, and mechanism for driving fasteners upwardly into the shoe to secure the upper in pulled-over position, of a source of supply 55 for fasteners in which they are positioned point downward, conduits arranged to extend upwardly over the fasteners as thus positioned and leading to points near the shoe for delivery of fasteners point upward to said fastener driving mechanism, and mechanism controlled by the upper pulling means for forcing fasteners upwardly from the source of supply into said conduits.

65 14. In a machine of the class described,

the combination with means for pulling an upper over a last positioned bottom downward, and mechanism for driving fasteners upwardly into the shoe to secure the upper in pulled-over position, of a source of supply 70 for fasteners in which they are positioned point downward, conduits arranged to extend upwardly over the fasteners as thus positioned and leading to points near the shoe for delivery of fasteners point upward to said fastener driving mechanism, and means dependent for its operation upon a movement of the upper pulling means and automatically operative to deliver a blast of air 75 for dislodging fasteners from said source of supply and forcing them into said conduits.

15. In a machine of the class described, the combination with means for pulling an upper over a last positioned bottom downward, of upper fastening mechanism including driving means arranged to drive a fastener upwardly into the shoe and movable transversely of the edge of the shoe bottom into and out of driving position, a conduit 80 extending to a position near the shoe for delivering fasteners point upward, a carrier member movable with said driving means and mounted to swing alternately into position to receive a fastener from said 85 conduit and into position to present the fastener in operative relation to the driving means, and means controlled by the upper pulling means for delivering a blast of air to force a fastener along said conduit.

16. In a machine of the class described, the combination with means for pulling an upper over a last positioned bottom downward, of driver bar arms mounted for movement at the toe end and at opposite sides of 105 the shoe into and out of position for driving tacks upwardly into the shoe, tack drivers on said arms, conduits leading to positions near the toe end and the opposite sides of the shoe for delivering tacks point 110 upward, tack carriers mounted on said driver bar arms for movement relatively to the arms into position to receive tacks from said conduits and into position to present the tacks to the drivers, and mechanism arranged to be rendered operative by movement of the upper pulling means for effecting the delivery of tacks into said conduits.

17. In a machine of the class described, the combination with means comprising 120 grippers and an operating cam slide for pulling an upper over a last positioned bottom downward, of driver bar arms mounted for movement at the toe end and at opposite sides of the shoe into and out of position 125 for driving tacks upwardly into the shoe, tack drivers on said arms, a tack separator arranged to support tacks point downward in separated position, conduits arranged to extend upwardly over the tacks on the 130

separator and leading to points near the toe end and the opposite sides of the shoe for delivering the tacks point upward, means controlled by said cam slide and automatically operative at a determinate time relatively to the operation of the upper pulling means to direct a blast of air against the tacks on the separator to lift them and force them into said conduits, and tack carriers 5 movably mounted on the driver bar arms 10 to receive the tacks from said conduits and to present them to the drivers.

18. In a machine of the class described, the combination with means for pulling an upper over a last positioned bottom downward, of tacker mechanisms for driving tacks upwardly at the toe end and at opposite sides of the forepart of the shoe to secure the upper in pulled-over position, a 15 tack separator arranged to support tacks point downward in separated position, conduits arranged to extend upwardly over the tacks on the separator and leading to the different tacker mechanisms for delivering 20 the tacks point upward to said mechanisms, and means arranged to be rendered operative by a movement of the upper pulling means for directing a blast of air against the tacks on the separator to lift them and 25 force them into said conduits.

19. In a machine of the class described, the combination with means for pulling an upper over a last positioned bottom downward in one period of the cycle of the machine, means for fastening the upper in a different period of the cycle, and controlling means automatically operative to bring the machine to a stop at the end of each period of the cycle, of pneumatic means automatically operative in one of the periods of the cycle to invert and deliver a fastener point upward to the upper fastening means.

20. In a machine of the class described, the combination with means for pulling an upper over a last in one period of the cycle

of the machine, means for fastening the upper in a different period of the cycle, and controlling means automatically operative to bring the machine to a stop at the end of each period of the cycle, of a conduit for 50 delivering upper securing fasteners to said fastening means, and spring operated pneumatic means arranged to be set in one period of the cycle and to be tripped in another period of the cycle for delivering a 55 blast of air to force a fastener along said conduit.

21. In a machine of the class described, the combination with means for pulling an upper over a last positioned bottom downward in one period of the cycle of the machine, upper fastening means for driving fasteners upwardly into the bottom of the shoe in a different period of the cycle, and controlling means automatically operative to 60 bring the machine to a stop at the end of each period of the cycle, of separating means for fasteners, conduits leading from said separating means to the upper fastening means and constructed to invert the fasteners and deliver them point upward, and means automatically operative in one of the 65 periods of the cycle to blow the fasteners along said conduits.

22. In a machine of the class described, the combination with upper pulling means movable in one direction to pull the upper and in the reverse direction to return to starting position, of fastening means for securing the upper in pulled-over position, 80 and pneumatic means controlled by the movements of the upper pulling means in said different directions for delivering fasteners to the fastening means.

In testimony whereof we have signed our 85 names to this specification.

ARTHUR ERNEST JERRAM.
JOSEPH GOULDBOURN.
FRED RICKS.
